ABSTRACT OF THE DISCLOSURE

Nonionic ethoxylated surfactants, which are known to be very desirable components in heavy duty cleaning products, suffer from the fact that they have limited solubility in solutions of alkaline electrolytes and thus are not soluble in alkaline builder concentrates. Addition of moderate amounts of substituted succinic acids overcomes this defect and permits the inclusion of these nonionics in built liquid detergent concentrates.

This invention relates to surfactant compositions which can be incorporated into built liquid detergent concentrates, and at the same time possess useful performance characteristics in dilute cleaning baths.

Broadly stated, the invention pertains to surfactant compositions that are soluble in solutions of alkaline builders having a high solids content.

An object of the invention pertains to surfactant compositions that are soluble in solutions of alkaline builders having a high solids content.

An object of the invention is to provide means for solubilizing polyethylene oxide containing nonionic surface active compositions into builder solutions.

A further object is to provide homogeneous built liquid detergents and alkaline cleaners containing polyethylene oxide nonionic surfactants and alkaline builders, characterized by the possession of low foaming properties even when used in high pressure automatic cleaning operations.

Alkaline cleaners are the most widely used means in industry for cleaning meal, glass, certain plastics, etc. In the metal-forming field, in particular, such cleaners are used to remove various types of soils such as cutting oils, grinding (buffing, stamping and drawing compounds. The alkaline cleaning solutions may be used in various types of cleaning methods and apparatus, e.g. soaking, spraying, electrolytic, et al.

Currently, the trend in industrial use of alkaline cleaners is in the direction of automated operations as a means of reducing manpower and time requirements. The preferred detergent products for these operations are aqueous built liquids containing surfactants and high levels of alkaline builders. The preferred surfactants are the nonionic ethoxylated type, for they have some or all of various desirable features such as superior detergent action, rapid wetting, low foaming capacity, soil defoaming capacity, emulsifying properties, free rinsing, etc.

All nonionic surfactants based on polyethylene oxide units as the hydrophilic portion, however, suffer from a basic deficiency. They have poor tolerance in solutions for alkaline electrolytes, and thus are not soluble at the levels of alkaline builders required for a practical liquid detergent concentrate. It is believed that this is due to the fact that the other oxygen atoms of the polyethoxy chain lose water of hydration excessively in alkaline builder solutions. In any event, the nonionic surfactants exhibit a cloud point whereby above this temperature the surfactant separates into a second phase.

Alkaline builders cause the cloud point to be lowered

2

to a point where phase separation occurs at ambient temperature. Increasing the number of ethoxy groups in the molecule does raise the cloud point in water or in builder solutions of low concentrations, but solubility at high builder levels cannot be achieved regardless how many ethylene oxide units are present. Moreover, to modify the nonionic structure as by incorporating ionic groups may improve alkali tolerance but will also alter the performance undesirably as well as increase the costs.

10 A particularly difficult part of the general problem of incorporating nonionic ethoxylated surfactants into aqueous alkaline builder concentrates is that of using low-foaming nonionic surfactants. This group of ethoxylates must have relatively low cloud points in dilute solutions in order to exhibit low foaming properties at use temperatures. Consequently, they have not heretofore been capable of being incorporated into builder solutions even at relatively low alkaline builder levels. Nonetheless, low foaming nonionics are especially desirable for incorporation into built liquid detergents since many of the automated cleaning machines employ a power washing cycle. Although their greater mechanical action enables power washers to give quicker and better cleaning action than is achieved by still soaking and the like, their one big drawback is their tendency to generate excessive foam, the air content of which reduces the cleaner's density and mechanical impact. The use of low foaming nonionic surfactants not only avoids this problem, but also serves to reduce the foam caused by certain soils such as proteinaceous matter.

The present invention has made it possible to incorporate nonionic polyethylene oxide type nonionics, such as the well known, commercially available Triton X-100, into alkaline builder solutions. This has been accomplished by blending together with those nonionics, in certain ratios of one to the other, certain substituted succinic acids. The effectiveness of such blends in making soluble in builder solutions nonionics which heretofore had no such properties is remarkably good. The presence of 40 the substituted succinic acids raises the cloud point of the nonionics in the builder solutions to such an extent that clear, homogeneous solutions are obtained at ambient temperatures. Other hydrotropes are known to have some solubilizing activity for nonionics in builder solutions, 45 but are unsatisfactory for most industrial applications because they require either too high a ratio of hydrotrope to nonionic or permit only such a relatively low concentration of builder as to make the resulting products have too little economic utility.

50 Another advantage derived from our novel utilization of the substituted succinic acids as part of the surfactant compositions of the present invention resides in the surprising fact that, unlike other hydrotropes, they do not adversely affect the properties or performance characteristics of the nonionics in the end-use baths. This particular characteristic is extremely important in power washing operations because any significant contribution of foam by the hydrotrope would make those materials useless.

55 The compositions of the present invention, which so effectively combine the property of solubility in highly built liquids with the performance properties of ethoxylated nonionics, essentially consist of blends of the following constituents:

60 25-90% of a substituted succinic acid,

where

70 R is an alkyl or alkenyl group, branched or straight chain, of 7 to 12 carbon atoms, and

10-75% of a nonionic polyethoxylated surfactant. Illustrative of the nonionic surfactants which may be employed are those from the group consisting of:

(1)

where

R is an alkoxy group whose alkyl portion has 8-18 C atoms, an alkyl amine whose alkyl portion has 8-18 C atoms, or an alkyl phenoxy group whose alkyl portion has 6 to 12 C atoms,

x=3-90,

R' is H, a C₁₋₄ alkyl group, benzyl, acetate, ethyl acetyl, acetal, or chloro group,

R'' is H, CH₃, or C₂H₅, and

(2) Ethylene oxide-propylene oxide block copolymer.

A preferred novel blend in accordance with the present invention is one in which the substituted succinic acid is the n-octenyl adduct, the nonionic polyethoxylate is a low-foaming polypropylene oxide terminated ethoxylated linear primary alcohol, and the ratio of the former to the latter varies between 1.5 and 2.

Optional materials which may be employed as the hydrotrope in place of the substituted succinic acids are compounds which can form the dicarboxylate ion upon addition to alkaline builder solutions as does substituted succinic acid. Such materials, for example, would include mono- or di- salts, alkyl esters, amides, and the anhydrides of alkyl or alkenyl succinic acids.

The nonionic surfactant component of the novel blends may be selected from compositions containing a hydrophobic portion and a hydrophilic portion, the latter portion consisting principally or entirely of polyethylene oxide units and characterized by the fact that the molecule does not ionize in alkaline solutions. Included in these compositions are ethylene oxide adducts containing amine groups which sometimes are classed as cationics but actually are nonionics in alkaline solutions, and "modified" ethylene oxide adducts such as those terminated with benzyl groups and polypropylene oxide chains.

The effectiveness of the above-described hydrotropes in solubilizing the polyethoxylated nonionic surfactants can readily be demonstrated by comparing them with a number of prior art solubilizers for nonionics in alkaline builder solutions. In making such comparisons it should be kept in mind that the objective is to provide a solubilizing agent which will allow the highest concentrations of alkaline builders, and which can be present at the minimum level for a given amount of nonionic surfactant. Accomplishing this objective is paramount for practical economic considerations. Built liquid detergents with low builder levels and consequently high water contents have excessively high packaging, shipping and handling costs per part of active ingredient. Secondly, it is desirable to have present a minimum amount of any component that does not directly contribute to cleaning action; hence the need to keep the amount of hydrotrope present down to the minimum possible consistent with its required solubilizing activity.

A striking illustration of the effectiveness of the present invention is had by comparing the solubilizing activity of various substituted succinic acids when blended with the benzyl ether of an ethoxylated higher alcohol. This low-foaming nonionic's solubility in alkaline builder is so poor that, for example, it is not soluble in solutions of potassium hydroxide having as little as 5% KOH present. Yet, when this same nonionic is blended with 80% n-octenyl succinic acid in accordance with the present invention the blend is soluble in as much as 35% KOH solutions, as indicated in Table I below which contains data regarding the solubility of 80/20 blends of potential hydrotropes and the benzyl terminated ethoxylate in 20% KOH solution.

In obtaining the data reported in Table I the comparison "standard" employed called for a test composition to be considered as having adequate solubility in a system if a clear, homogeneous solution was obtained over the temperature range of 19-450 C. It will be noted from Table I that not all of the substituted succinic acid compositions are satisfactory hydrotropes. Whereas, under the conditions of test there shown, straight chain alkenyls of 8, 10 and a blend of 7 and 9 carbon atoms, branched chain alkenyls of 9 and 12 carbon atoms and a straight chain alkyl of 8 carbon atoms are effective solubilizers, straight chain alkenyls having 6 carbon atoms are not suitable and neither are compositions with an alkyl amino group or an aromatic group. The data further indicate that an alkyl chain above 12 carbon atoms will not be active at concentrations of 20% KOH or higher, and therefore would be considered unsatisfactory.

Numerous materials besides those listed in Table I were tested, including compositions with previously recognized hydrotropic activity as well as many experimental compositions. None of those materials, other than the substituted succinic acids, gave adequate solubilization of the nonionic surfactant when subjected to this screening. The unsatisfactory materials, which includes Na benzene sulfonate, Na toluene sulfonate, Na xylene sulfonate, sodium methyl naphthalene sulfonate, sodium dodecyl diphenylether disulfonate, and n-decyl monophosphate ester, the results obtained therewith, are reported in Table II below. Other compositions found to be ineffective solubilizers include Na butyl sulfonate, Na heptyl sulfonate, succinic acid, di-sodium phthalate, di-sodium alpha sulfo octanoic acid, di-sodium alpha sulfo stearic acid, Na n-decyl monophosphate, Na benzoate, Na nonanoate, and sulfonated naphthalene-formaldehyde condensate.

TABLE I.—SOLUBILIZATION OF BENZYL ETHER OF ETHOXYLATED ALCOHOL¹ IN ALKALINE SOLUTIONS BY VARIOUS HYDROTROPS HAVING FORMULA—

Substituent R in acid formula	Solubility of blend ² in 20% KOH solution	Maximum percent KOH in which material shows solubilizing activity

¹ C₁₂-₁₅H₂₅-₃₁O(CH₂CH₂O)₁₁CH₂C₆H₅.² "E" in certain of the examples of hydrotropes refers to ethylene oxide units.³ 5% of a blend consisting of 1 part of C₁₂-₁₅H₂₅-₃₁O(CH₂CH₂O)₁₁CH₂C₆H₅ and 4 parts of the hydrotrope.

Since the data in Table I illustrate the ability of various substituted succinic acids to solubilize a particular nonionic in builder solution, it naturally will be of interest to compare data which illustrate the ability of at least one of the substituted succinic acid hydrotropes to solubilize examples of a number of nonionics under the same conditions. Since polyethoxylated alcohols are the nonionics of principal interest, due to their well-known reputation for being among the most effective of all known detergents, major types of those ethoxylates were screened with the results set forth in Table III below. Using a 60/40 ratio (hydrotrope/nonionic) the ethoxylates which were solubilized into 20% KOH included adducts of alkylphenol, higher alkyl (as much as C₁₂) alcohols, alkyl amine, polysiloxane, and alkyl acetylenic glycol; other ethoxylated nonionic surfactants include a block copolymer of propylene oxide and ethylene oxide, two polypropylene oxide terminated alcohol ethoxylates and a chloro-terminated ethoxylated alcohol.

The data in Table III clearly indicate that the effect of the hydrotropes of the present invention is quite a general one for all polyethoxylate nonionics, although it should be understood that not all such nonionics will be effective under the conditions described for the examples given in that table. Likewise, it should be understood that not all nonionics are equal with regard to their ease of solubilization, and the minimum amount of hydrotrope required to effect their solubilization will therefore vary.

In general, the nonionic surfactants which will be most readily solubilized into builder solutions by the substituted succinic acid hydrotropes of the present invention are those which have a terminal hydroxyl group. Thus, those nonionics would certainly be the preferred types of surfactants. Included in this category would also be compositions which, upon addition to alkaline builders, would

produce a terminal hydroxyl group, an example being an acetate ester such as the last nonionic listed in Table III.

¹ 5% surfactant into 20% KOH; surfactant is a 60/40 blend of n-octenyl succinic acid/nonionic.² Illustrative of other nonionic surfactant compositions which could be blended with the same or other substituted succinic acids, at various ratios (and naturally with varied performance), to give an alkali soluble product are: t-octyl phenol E₆, t-octyl phenol E₃₀, hexyl phenol E₉, t-octyl phenyl E₁₀ b-butyl ether, n-octyloxy E₃, octadecyloxy E₁₂, C₁₂ amine E₄₀P₅₀, sec. C₁₁-₁₅H₂₅-₄₁OEt ethyl acetal, andStill other nonionics which are suitable are polyethylene oxide adducts of polypropylene oxide where the molecular weight of the propylene oxide chain, and the weight percent of ethylene oxide, are respectively: 1,001-1,200 and 40%, 1,501-1,800 and 20%, 1,501-1,800 and 80%, 3,200-3,500 and 30%.

³ Nonionics alone are insoluble in 20% KOH.

NOTE.—E refers to ethylene oxide units, and "P" refers to units of propylene oxide.

The effective ratios of hydrotrope to nonionics have been investigated, with the conclusion that any ratio would have some nonionic solubilizing effect in builder solutions, so that the ratio of choice almost becomes an arbitrary selection. The upper limit, of course, is dictated principally by economics. The hydrotrope portion, it should be noted, essentially is a diluent since the basic goal is to obtain the performance of the nonionic portion. As a practical matter, a 9/1 ratio is considered to be the effective maximum; and the lower effective limit depends on the nonionic chosen together with the particular builder system of interest. Actually, any amount of hydrotrope added to a nonionic will raise its cloud point somewhat; the higher the ratio the greater the level of builder which can be tolerated.

As a rule, we have found, a minimum of 1 part hydrotrope to 3 parts nonionic are needed for solubility at reasonable builder levels. In Table IV, which contains data regarding results obtained with different ratios of substituted succinic acid to nonionic, the system chosen for illustration resulted in ratios of 9 to 0.33 (25/75) proving to be soluble, a clear solution being obtained at least from 10-45° C. In this system a 0.25 ratio proved to be inadequately soluble.

Table IV.—Effect of varying the ratio of substituted succinic acid to nonionic

Ratio of n-octenyl succinic acid to nonionic*:	Solubility in 20% at 5% surfactant KOH solution
90/10	Clear 0-100° C.
60/40	Clear 0-98° C.

25/75	Clear 0-45° C.
20/80	Clear 0-180° C.

*Octyl phenyl E₁₀ ("E" = ethylene oxide units).

The solubility of the blends of alkyl or alkenyl succinic acids and nonionic ethoxylates is, of course, not limited to potassium hydroxide solutions. To demonstrate this fact examples are given in Table V below of several blends in sodium metasilicate, tetrapotassium pyrophosphate (TKPP) and mixed builder solutions.

TABLE V.—EFFECTIVENESS OF VARIOUS HYDROTROPES IN VARIOUS ALKALINE SOLUTIONS

Various ones of the blends in Table V have been tested to determine their particular utility in a number of use situations. These formulations were added to cleaning baths at levels of 1 part of formulation to 50-1000 parts of water. Example No. 5 shows very low foam and effectively removes oils from steel under industrial spray metal cleaning conditions. Example No. 7 exhibits good detergency, low foam, and the ability to defoam proteinaceous food soils in mechanical dishwashing operations. Example No. 3 is a suitable for use in commercial laundering, particularly with heavily soiled cotton and polyester-cotton fabrics.

Regarding the methods of preparation of the components of the novel blends described above, it should be noted that any of the many conventional techniques for preparing the nonionics and the substituted succinic acids may be employed. Preferably, the substituted succinic acids may be prepared by heating a mixture of olefin and maleic anhydride in a closed vessel for a suitable period of time. The alkenylsuccinic acid anhydride so formed can be purified by distillation or, if a light color is not required and some loss in effectiveness can be tolerated, the reaction mixture can be used without distillation. Although in some applications the anhydride can be used directly, in others it is more advantageous to use the acid. Conversion of the anhydride to the acid can be effected by merely contacting the anhydride with the required amount of water at elevated temperatures. Other derivatives of the anhydride, such as esters, amides, salts and saturated alkyl substituted derivatives can be used but are not as convenient to formulate and are more expensive to obtain.

From the foregoing specification it will be apparent to those skilled in the art that the compositions of the present invention are wide in their scope, both with regard to their formulation and their use, and are not necessarily limited by the examples hereinabove disclosed.

We claim:

1. A surface active composition consisting essentially of:

(a) 25-90% of a substituted succinic acid,

where R the sole substituent is an alkyl or alkenyl group, branched or straight chain, of 7 to 12 C atoms, and

(b) 10-75% of a nonionic polyethoxylated surface active agent.

2. The composition of claim 1 in which the agent is selected from one of a linear primary C₁₀₋₁₂ alcohol E₄P₃, a linear primary C₈₋₁₀ alcohol E₃P₃, a linear primary C₁₀ alcohol E₁₀Cl, a linear primary C₁₀₋₁₂ alcohol E₄P₃ acetate ester, and ethylene oxide and propylene oxide

block copolymer E₃P₂₈ E₃, and "E" "P" designation representing ethylene oxide and propylene oxide.

3. The composition of claim 1 in which the nonionic polyethoxylated surface active agent is selected from the group consisting of:

(a)

where

R is an alkoxy group whose alkyl portion has 8-18 C atoms, an alkyl amine whose alkyl portion has 8-18 C atoms, or an alkyl phenoxy group whose alkyl portion has 6 to 12 C atoms,

x=3-90,

R¹ is H, a C₁₋₄ alkyl group, benzyl, acetyl, ethyl acetal, or chloro group,

R² is H, CH₃ or C₂H₅,

and

(b) ethylene oxide-propylene oxide block copolymers.

4. A surface active composition consisting essentially of a blend containing

(a) 25-90% of a substituted succinic acid,

where R is an alkyl or alkenyl group, branched or straight chain of 7 to 12 C atoms, and

(b) 10-75% of a low foaming polypropylene oxide terminated ethoxylated linear primary alcohol of 8-12 carbons or the acetate ester thereof.

5. The composition of claim 4 in which the ratio of the substituted succinic acid to the nonionic surfactant is between about 1.5 and 2.

6. The composition of claim 4 in which R is selected from the group consisting of n-heptenyl-nonenyl (1/1), n-octenyl, n-octyl, branched nonenyl, n-decetyl, and branched dodecetyl.

7. The composition of claim 3 in which the nonionic polyethoxylated surface active agent is selected from the group consisting of t-octylphenyl E₅, t-octylphenyl E₁₀, t-octylphenyl E₃₀, hexylphenyl E₉, nonylphenyl E₁₀, dodecylphenyl E₁₀, t-octylphenyl E₁₀, t-butyl ether, n-octyl-oxy E₆, octadecyloxy E₁₂, C₁₂ amine E₄₀P₅₀,

ethyl acetal, linear secondary alkyl alcohol E₉ adduct in which the alkyl group has 11-15 C atoms, linear primary alkyl alcohol E₈ adduct in which the alkyl group has 12 C atoms, alkyl amine E₁₅ in which the alkyl group has 12-15 C atoms, polydimethyl siloxane-ethylene oxide adduct, alkyl acetylenic glycol E₁₀ in which the alkyl group has 14 C atoms, ethylene oxide-propylene oxide block copolymers where the propylene oxide block(s) has at least 15 units and the ethylene oxide block(s) would represent between 10 and 80 weight percent of the total, linear primary alkyl alcohol E₄P₃ in which the alkyl group has 10-12 C atoms, linear primary alkyl E₃P₃ in which the alkyl group has 8-10 C atoms, linear primary alkyl E₁₀Cl in which the alkyl group has 10 C atoms, linear primary alkyl E₄P₃ acetate ester in which the alkyl group has 10-12 C atoms, the "E" and "P" designations respectively representing ethylene oxide and propylene oxide.

8. A surface active composition consisting essentially of:

(a) 25 to 95% of a substituted alkyl or alkenyl succinic acids of 7-12 carbons selected from the group consisting of the mono- and di-sodium and potassium salts, dimethyl esters, and the anhydrides of said acids, which upon addition to alkaline solutions gives the corresponding dicarboxylate ion of said acids, and

(b) 10-75% of a nonionic polyethoxylated surface active agent. 3,231,587 1/1966 Rense 252-356
